UNITED STATES PATENT OFFICE.

WILLIAM ANSON DULMAGE, OF HAMILTON, ONTARIO, CANADA.

SAMPLE-STRIP-HOLDING DEVICE FOR CLOTH-ROLLS AND THE LIKE.

1,249,924.

Specification of Letters Patent.

Patented Dec. 11, 1917.

Application filed September 1, 1916. Serial No. 118,132.

To all whom it may concern:

Be it known that I, WILLIAM ANSON DULMAGE, of the city of Hamilton, in the county of Wentworth, Province of Ontario, Canada, have invented certain new and useful Improvements in Sample-Strip-Holding Devices for Cloth-Rolls and the like, of which the following is the specification.

My invention relates to improvements in sample strip holding devices for cloth rolls and the like and the object of the invention is to devise a sample holder for a long strip of sample material cut clear across the width of the goods by which the sample may be easily and quickly inserted in the roll and held between the cloth board and the goods thereon so that the strip may be drawn out and a portion cut off therefrom from time to time as required and it consists essentially of a sample strip supporting structure designed to be slipped longitudinally into the cloth roll and having a cross slot in proximity to its inner end and through which the strip of material when doubled crosswise is passed and extended longitudinally against one face of the holder, the free ends lying one against the opposite face of the support, one end protruding beyond the end of the cloth board and the other against the double strip as hereinafter more particularly explained by the following specification.

Figure 1 represents a perspective view of one end of a cloth roll showing my sample supporting device inserted therein.

Fig. 2 is an enlarged perspective view of the sample strip support.

Fig. 3 is a longitudinal section through the sample strip support showing the sample strip in position thereon.

In the drawings like letters of reference indicate corresponding parts in each figure.

1 indicates a portion of a cloth roll, and 2 the cloth board around which the material 45 is wrapped to form the roll; 3 indicates the sample strip support. In Figs. 2 and 3 this support comprises a central strip portion having a cross slot 4 at one end thereof and edge ribs 5 and 6 extending from the upper 50 face and edge ribs 7 and 8 extending from the lower face whereby a flat groove is formed for the purpose of relieving the sample strip 9 from the pressure of the goods forming the coil so that it may be 55 readily drawn out as required and as well serve as a central guideway on the upper

and lower face of the holder. The sample strip 9 is folded intermediately of its length as at 10, the double portion being passed through the slot 4 and drawn longitudinally 60 of the support toward the outer end thereof as shown in Fig. 3, the free end 10^x of the strip being passed longitudinally from the slot 4 against the lower face of the holder so as to protrude at 11 from the end of the 65 cloth roll. The opposite free end 10^y is passed in the opposite direction and around the end of the holder and longitudinally over the double portion 10 as indicated in Fig. 3. When the strip is so placed upon 70 the holder the holder is slipped into the roll over the cloth board, the lower ribs 7 and 8 resting upon the cloth board so as to form an intermediate guideway through which the lower portion 10^x of the sample 75 strip may be freely drawn. The outer end of the strip portion 3 of the holder may be provided with upturned lug portions 3^x and 3^y which might be used merely to indicate the position of the sample holder so the 80 sample strip may be readily located in the piece of goods or on which can be inscribed respectively the price and width of the goods forming the cloth roll.

From this description it will be seen that 85 I have devised a very simple form of sample holder which may be easily and quickly inserted in position within the cloth roll and which will be adapted to hold a strip of maximum length and from which the 90 strip may be easily and quickly drawn whenever desired to the required length so that a sample of the goods forming the roll may be cut off therefrom.

What I claim as my invention is:

1. A sample strip support for cloth rolls comprising a supporting structure adapted to be slipped into the cloth roll and having a cross slot forming an end bridge at its inner end through which slot the double intermediate portion of the strip is drawn so as to lie doubled against one face of the support, one free end extending through the slot under and back over the bridge so as to lie on the double end, and the other free 105 end of the strip extending forward and lying against the opposite face of the support and so as to protrude from the end of the roll.

2. A sample strip for cloth rolls comprising a supporting structure adapted to be slipped into the cloth roll and having a cross

slot at its inner end through which the double intermediate portion of the strip is drawn so as to lie against one face of the support with one free end of the strip lying 5 against the opposite face of the support and so as to protrude from the end of the roll and edge rib portions extending from each edge of the support from end to end and above the opposite faces to relieve the pressure on the sample strip on both sides from 10 the goods forming the roll.

3. A sample strip support for cloth rolls comprising a supporting structure adapted to be slipped into the cloth roll and having a 15 cross slot at its inner end through which the double intermediate portion of the strip is drawn so as to lie against one face of the support with one free end of the strip lying against the opposite face of the support so

as to protrude from the end of the roll, and 20 guiding portions extending from each edge of the upper and lower face of the support.

4. A sample strip support for cloth rolls comprising a supporting structure to be slipped longitudinally into the roll and to 25 hold a sample strip freely in place within the roll so that such strip may be drawn out longitudinally therefrom when desired, end lugs having an unobstructed space between them and carried on the outer end of the 30 support and means at each side to form guideways to insure the sample strip being withdrawn straight from the support.

WILLIAM ANSON DULMAGE.
